UNITED STATES PATENT OFFICE.

HAROLD W. CLARK, OF ALLIANCE, OHIO, ASSIGNOR TO THE ALLIANCE MACHINE COMPANY, OF ALLIANCE, OHIO, A CORPORATION OF OHIO.

BRAKE.

Application filed December 19, 1921. Serial No. 523,275.

To all whom it may concern:

Be it known that I, HAROLD W. CLARK, residing at Alliance, in the county of Stark and State of Ohio, have invented a new and 5 useful Improvement in Brakes, of which the following is a full, clear, and exact description.

My invention relates to brakes of the type wherein shoes are pressed against a rotating 10 drum, and is designed to provide a brake of this character wherein substantially parallel motion is given to the shoe or shoes and substantially no strain is placed on the shaft carrying the brake drum. It is especially 15 adapted for hoists and cranes wherein the shoes are operated magnetically, but may be used generally.

In the accompanying drawings, which show two forms of my invention:

20 Figure 1 is a plan view of the preferred form;

Figure 2 is a longitudinal section on the line II—II of Figure 1;

25 Figure 3 is a view similar to Figure 2, but showing a modified form; and

Figures 4 and 5 are detail perspective views of parts employed in the form of Figure 3.

In the preferred form of construction 30 shown in Figures 1 and 2; 1, 1 are the side plates of a supporting frame, having fulcrum pins or shafts 4 and 5 extending between and through their upper and lower portions. On the central parts of these

35 shafts 4 and 5 are mounted brake levers 2 and 3, which in the form shown are operatively connected with the plunger 7 of a solenoid 6. As shown, the lower lever 2 extends through a slot in the lower part of 40 the plunger and has a loose pin connection 8 therewith, while the lever 3 extends through a slot in the enlarged head of a pin 9 screwed into the upper end of the plunger and has a loose pivotal connection 10 therewith.

On the shafts 4 and 5 are also mounted 45 connectors 14, each comprising a pair of triangular shaped plates having at their forward ends a set of adjusting holes, any one of which may be brought into registry with corresponding holes in the forwardly projecting end of its operating lever. 11, 12 and 13 designate the holes in the levers, and 15, 16 and 17 the holes in the connectors.

55 Each pair of connectors embraces the corre-

sponding lever and is provided with pins connecting with the braking members 22 and 23. As shown, the pin 18 extends through the upper portions of the upper plates 14 and through the upper ends of the pair of braking members 22, while the lower pin 19 of the upper plates extends through the upper ends of the braking members 23. Similarly, the pin 20 of the lower plates extends through the lower end of the braking members 22, while the lower pin 21 of the lower plates extends through the lower end of the braking members 23.

Either the levers or the connectors should be loosely mounted on the pins or shafts 4 and 5 to allow any one of the holes in the levers to be brought into registry with the holes in the plates. In the form shown, the end holes 13 are connected by pins with the end holes 17; but by removing this pin and 70 swinging the plates slightly relative to the lever, any one of the holes may be brought into registry, thus giving an adjustment for wear. This is the main object of providing 75 the link connections between the levers and 80 the braking members.

The brake shoes 24 and 25 are secured between the pairs of braking members 22 and 23, and their surfaces, of course, conform to the surface of the brake drum 26, carried on the shaft 27. The distances from the center of the pin 5 and the centers of the pins 18 and 19 are preferably alike, and the same spacing is preferably used for the pins 4, 20 and 21.

90 In the form of Figures 3, 4 and 5 the connecting links between the levers and the braking members are done away with, and adjustment is had by screw pins 28 and 9^a, screwed into the opposite ends of the solenoid plunger. These pins may be screwed in and out, thus giving the desired adjustment for wear or otherwise. In this form, the levers 2^a and 3^a are fulcrumed on the pins 4^a and 5^a, and their forward ends are 95 enlarged or provided with projections which are pinned directly to the ends of the pairs of brake members 22^a and 23^a. In these figures, parts shown in Figures 1 and 2 are 100 designated by the same numerals with the letter "a" applied.

The operation of my device is as follows: the operation of the device shown in Figures 1 and 2 being first explained.

110 In the position shown in Figure 2, the

solenoid 6 is de-energized and the armature has been moved by gravity to its lowermost position, and the brakes are applied by the weight of the armature acting through the 5 levers 2 and 3.

- The downward movement of the armature 7 carries with it the ends of the brake levers 2 and 3, thereby rotating the levers 2 and 3 and the members 14 around the pins 4 and 5. 10 This movement gives the points 18, 19, 20 and 21 a counterclockwise movement. The points 18 and 20 being above the pins cause the brake member 22 and the brake shoe carried thereby to move to the left, and the 15 brake member 23 and the brake shoe 25 carried thereby are moved to the right, since the points 19 and 21 are below the pins 4 and 5, respectively. This movement causes both brake shoes to engage the surface of 20 the brake drum and the brakes are therefore applied. The equal movement of the ends of the brake members 22 and 23 around the pins 4 and 5 moves the ends of the brake shoes 24 and 25 an equal amount relative to 25 the brake drum. The pins 4 and 5 are diametrically opposite each other and due to the arrangement illustrated, side strains on the shaft 27 carrying the brake drum are avoided. 30 When it is desired to release the brakes, the solenoid 6 is energized, thus raising the armature 7 into engagement with stop 30 and rotating the brake arms 2 and 3 in a clockwise direction around the pins 4 and 5. 35 This rotation moves the brake shoes 24 and 25 away from the brake drum and thus releases the brakes. The equal movement of both ends of the brake shoes away from the drum avoids any drag of the shoes on the 40 drum.

After the brake has been in operation for some time, the brake shoes become worn and in order for the shoes to grip the drum sufficiently, the armature 7 must move to an undesirable downward position. This condition may be remedied by adjusting the relative position of the members 14 with respect to the levers 2 and 3. This adjustment is as follows:

- 50 In order to tighten the brakes, the connecting pins are removed from the holes 13 and the holes 16 in the members 14 are brought into register with the holes 12 in the brake levers 2 and 3. This causes a 55 slight counterclockwise rotation of the members 14 around the pins 4 and 5, which it will be noted is in a direction to bring the brake shoes toward the brake drum. This brings the brake shoes closer to the brake 60 drum with a given position of the brake levers 2 and 3 than was the case when the connecting pins were in the holes 13.

In order to adjust the relation of the brake levers 2 and 3 with respect to each 65 other, the pin 10 is removed and the bolt 9

screwed into or out of the armature 7 to effect the required adjustment. Once this adjustment is secured, it remains fixed.

The operation of the device shown in Figure 3 is identical with that above described. 70 The adjustment of the brake shoes with respect to the drum, however, is accomplished differently from that of the device shown in Figures 1 and 2. In the device of Figure 3, this adjustment is accomplished by removing the pins 10^a and 29 which connect the brake levers 3^a and 2^a, respectively, to the armature. If it is desired to tighten the brakes for a given position of the armature in the coil, the bolt 9^a is screwed into the 75 armature 7^a and the bolt 28 is screwed out of the armature a corresponding amount. The brake levers 2^a and 3^a remain unchanged relative to each other, but are lower for a given position of the armature in the coil, 80 thus moving the brake shoe close to the drum. 85

By reason of the adjustments, the brakes are applied while the armature remains inside the coil sufficiently to be quickly lifted 90 to release the brakes when the coil is energized and the adjustment is such that the brakes are fully released when the armature has moved to its maximum upward position 95 against its stop.

My invention has many advantages resulting from the structure and arrangement of the parts as described, and among which may be specifically mentioned that the brake shoes are moved a substantially equal distance at both ends relative to the brake drum, thus eliminating any drag on the drum; the actuating members for the brake shoes are pivotally connected at both ends to a supporting structure, thus eliminating all 100 side strains on the brake drum shaft, and simple means are provided for making the necessary adjustments. Other advantages 105 will be apparent to those skilled in the art.

Many changes may be made in the details 110 of construction of my device, without departing from the spirit of my invention.

I claim:

1. In a brake device, a brake drum, a plurality of bodily movable brake shoes, and actuating means operatively connected to said shoes and maintaining the same equidistantly spaced from the center of said drum at all times and in concentric relation thereto, substantially as described. 115
2. In a brake device, a brake drum, a plurality of bodily movable brake shoes, and pivotally mounted actuating means operatively connected to said shoes and maintaining the same equidistantly spaced from the center of said drum at all times and in concentric relation thereto, substantially as described. 120
3. In a brake device, a brake drum, a plurality of bodily movable brake shoes, and 125

- actuating means pivotally mounted intermediate adjacent ends of the brake shoes and operatively connected thereto for maintaining said shoes equidistantly spaced 5 from the center of said drum and in concentric relation thereto at all times, substantially as described.
4. In a brake device, the combination of a brake drum, a plurality of brake members 10 extending around said drum, eccentric means connected to the adjacent ends of said brake members, and means actuating said eccentric means whereby an equal movement is always simultaneously imparted to the ends of said drum members upon every movement of said eccentric means, substantially as described.
5. In a brake device, the combination of a brake drum, brake members encircling said 20 drum, eccentric means pivotally mounted independently of said members and connecting the adjacent ends thereof, and means for actuating said eccentric means to cause an equal angular movement of said brake 25 members about the pivot points of said eccentric means, substantially as described.
6. In a brake device, the combination of a brake drum, brake members encircling said drum, means connecting the adjacent 30 ends of said members together, said means having fixed pivotal mountings between the ends of said members, and means moving said connecting means around said mountings to simultaneously move said members 35 radially toward and away from the drum, substantially as described.
7. In a brake device, the combination of a brake drum, two brake members encircling said drum, two substantially parallel members 40 rotatable about fixed axes and connecting the ends of said brake members, and means connecting and rotating said parallel members for actuating the brake members, substantially as described.
8. In a brake device, the combination of two brake members adapted to encircle a 45 brake drum and having their ends in adjacent relationship, an actuating lever pivoted between and independently of each pair of adjacent ends of said brake members 50 and operatively connected thereto, and means for simultaneously actuating said levers to move said brake members toward or away from each other, substantially as described. 55
9. In a brake device, the combination of two brake members adapted to encircle a brake drum, rotatable means connecting the adjacent ends of said members and rotatable at all times about fixed axes, and actuating 60 means for said connecting means, substantially as described.
10. In a brake device, the combination of two brake members adapted to encircle a 65 brake drum, rotatable means connecting the adjacent ends of said members, and rotatable at all times about fixed axes, and adjustable means between said connecting means and said actuating means, substantially as described. 70
11. In a brake device, the combination of brake members, brake shoes thereon, rotatable levers, each connecting the adjacent ends of said members and having a fixed pivotal mounting therebetween, a solenoid 75 armature interconnecting said levers, and a coil for actuating said levers through said armature, substantially as described.
12. In a brake device, the combination of 80 brake members pivotally interconnected at points substantially diametrically opposite, and means for always moving both ends of said members simultaneously and through equal angles, substantially as described.
13. In a brake device, the combination of 85 a brake drum, brake members operatively related thereto, brake shoes on said members, levers each connecting an adjacent end of said members, and each having a fixed pivotal mounting between said ends, power-operated means connecting the free ends of said levers, and means for effecting relative adjustment of said levers, substantially as described. 90
- In testimony whereof I have hereunto 95 set my hand.

HAROLD W. CLARK.
